UNITED STATES PATENT OFFICE.

ARTHUR M. HOOD, OF INDIANAPOLIS, INDIANA, ASSIGNOR TO THE GREENSTREET FOLDING BOX MACHINE COMPANY, OF CRAWFORDSVILLE, INDIANA, A CORPORATION OF ARIZONA.

WIRE-BOUND-BOX MACHINE.

1,107,216.

Specification of Letters Patent. Patented Aug. 11, 1914.

Application filed June 20, 1910, Serial No. 567,881. Renewed October 27, 1913. Serial No. 797,652.

To all whom it may concern:

Be it known that I, ARTHUR M. HOOD, a citizen of the United States, residing at Indianapolis, in the county of Marion and 5 State of Indiana, have invented a new and useful Wire-Bound-Box Machine, of which the following is a specification.

The object of my present invention is to produce a box machine requiring a minimum amount of labor and intelligence in its 10 operation and of such character that cleats may be placed in proper order upon a carrier which will deliver them past automatically operating spacing mechanism in such 15 manner that they will be definitely and accurately spaced with relation to a spaced cleat carrier and by it be delivered to stapling mechanism, mechanism being also provided to form a definite and accurate gage 20 by means of which the sheet material may be accurately placed by the supervising operator under whose immediate supervision the stapling mechanism will operate.

This invention also contemplates such improvements in detail of construction as may 25 be hereinafter more fully pointed out and claimed.

The accompanying drawings illustrate the invention.

30 Figure 1 is a plan of the complete machine on a very small scale; Fig. 2 is a side elevation on the same scale as Fig. 1; Fig. 3 a vertical section on line 3, 3 of Fig. 1 but on a larger scale; Fig. 4 a section on line 4, 4 of Fig. 3; Fig. 5 a section on line 5, 5 of Fig. 3; Fig. 6 a fragmentary side elevation of a portion of the automatic cleat spacer and adjacent portions of two spaced cleats; Fig. 7 a plan of the parts shown in Fig. 6; 35 Fig. 8 a side elevation, on a larger scale, of the automatic cleat-spacing mechanism and adjacent parts; Fig. 9 a plan of the parts shown in Fig. 8; Fig. 10 a transverse sectional detail of the parts shown in Figs. 40 45 and 9; Fig. 11 a fragmentary detail of a portion of the cleat retarding mechanism; Fig. 12 a plan in partial horizontal section of the sheet-spacing mechanism; Fig. 13 an elevation of the sheet spacer; Fig. 14 a fragmentary detail of a modified form of cleat and the coöperating spacer, and Fig. 15 a plan of a modified guide for the sheet spacer.

In the drawings, 20 indicates the main supporting frame of the machine having 50 two horizontal cleat guides or runways 21,

21 at least one of which is transversely adjustable toward the other by any suitable means, such for instance as adjusting screws 22 of a well-known type, these adjusting screws being preferably connected for simultaneous movement by sprocket chains 23. The cleat guides 21, at an intermediate point in their length, pass over or are associated with an anvil beam 24 above which are arranged stapling heads 25 by means of which suitable staples may be driven into the material of the blank and straddling strengthening or binding wires 26. Thus far the mechanism is very similar to that now commonly in use and therefore needs no further 65 description, the exact character of the stapling mechanism being entirely immaterial.

At the receiving end of each cleat guide 21 is a cleat channel 31 into which cleats 32, of any desired form, may be fed in desired length sequences. Any suitable means may be provided for insuring movement of the cleats through these channels 31 but probably the most convenient means will be endless chains 33, 33 one mounted in the bottom of each channel 31 and arranged so that the cleats will rest directly upon the upper length of the chain. These chains may be provided with cleat-engaging lugs 34. The chains 33, if they are provided with the cleat-engaging lugs 34, should be driven by a friction train which constantly provides a light but fairly rapid driving force which, however, may be overcome by sufficient resistance offered to the movement of the 70 cleats. For this purpose the forward ends of the chains 33 are passed over sprocket wheels 35 carried by a shaft 36 journaled on the main frame. The sprocket wheel 35 which is adjacent the adjustable cleat guide 21 is splined upon the shaft 36 and associated with the guide in such way as to partake of its transverse adjustment. Shaft 36 is provided at one end with a hand wheel 37, by means of which it may be rotated, and at the opposite end is provided with a pulley 38 receiving a belt 39 coming from a pulley 41 carried by a continuously driven shaft 42. An idler 43, having a spring tension member 44, engages the belt 39 so that the driving effect of the belt upon the pulley 38 may be readily adjusted and controlled.

The sprocket wheels 35 are arranged immediately to the rear of positive feed chains 45, or other suitable positive cleat-engaging 100

and space-maintaining means, arranged to positively engage the cleats and carry the same across the plane of the stapling mechanism so that, until one or two staples have been driven into any particular cleat, the said cleat will be maintained in its definite relationship to the preceding and following cleats by said cleat-engaging means. For this purpose chains 45 are provided with 5 sharpened lugs 46 which are adapted to sink into the sides of the cleats and these chains are backed up by stationary guide or backing strip 47. Coöperating with the chains 45, and spaced therefrom a distance equal 10 to the thickness of the cleats, is an abutment structure which may be either the flange 48 of guide 21 or a holder 49 carrying a plurality of anti-friction rollers 50, suitable means being provided for adjustment of 15 abutment 48 and the backing strip 47 to accommodate different thicknesses of cleats if desired.

Before the cleats pass into the control of the spaced-cleat carrier 45 it is necessary 20 that mechanism be provided for definitely spacing the cleats with relation to each other but this spacing mechanism need only be in operative position just long enough to insure 25 a proper engagement of the carrier 45 with the freshly entered and properly spaced cleat. This cleat spacing mechanism, besides being automatic in its operation, should, in order to facilitate the commercial production of boxes, be of such character as to 30 not only properly space the cleats of each blank but also such as to give the proper spacing between cleats of adjacent blanks so 35 that the operation of the machine, in the production of successive blanks, may be continuous.

The ordinary box will be formed of four pieces to make a four-sided box and the cleats of these four sides must be regularly spaced with relation to each other while the 40 last section of each blank and the first section of the succeeding blank must ordinarily be spaced a greater distance apart in order to provide a sufficient excess of binding wire to permit the proper connection of the ends of 45 the binding wire of each blank.

In the present drawings spacing mechanism has been shown especially adapted for the production of four-sided box blanks but it will be readily understood that, without 50 material change, the essential feature of the construction to be described may be as readily applied in the production of box blanks having any desired number of sides. The spacing mechanism fundamentally comprises, for each cleat guideway, a spacing member having portions which will be automatically successively brought into position at the rear ends of the cleats and be there maintained temporarily until some means 55 has been provided for maintaining the spaced

relationship between said cleat and the next succeeding cleat, whereupon the spacing member may be withdrawn and automatically returned to position where it may automatically assume another spacing position. 70 In the present machine this fundamental feature has been embodied in a form by which every fourth cleat will be more distantly spaced from its preceding cleat.

Proceeding now to a description of the 75 spacing mechanism, it will be seen that, closely adjacent the receiving ends of the spaced-clear carriers 45 and the discharging ends of the cleat-feeding carriers, is spacer wheel 51 which is provided with three spacing fingers 52 each of which is provided with a tip 53 adapted to be projected between the adjacent ends of two cleats 32.

In the drawings the cleats 32 which happen to be illustrated, are of the mortise-and-tenon type and for that reason the fingers 52 are thin enough to project upwardly through the mortise 32' and the tips 53 are transversely extended to engage the cleat at one side of the mortise. Each wheel 51 also carries a broader finger 54 which is provided with two spacing tips 55, 55 similar to the tips 53 but arranged more closely together and at a distance equal to the distance desired between the last cleat of one blank and 90 the first cleat of the next blank, so as to operate as a single spacing member. Each of the fingers 52 and 54 is so formed with a back edge 56 as to clear the sides of the cleats, as clearly illustrated in dotted lines 95 in Fig. 8.

The two wheels 51 are positively connected for simultaneous rotation by means of a shaft 57 which, however, is frictionally driven by belt 58 from the constantly rotating shaft 42, the arrangement being such that a very slight obstruction to rotation of either of the wheels 51 will prevent rotation of both although they are constantly under a rotative force which tends to rotate them together as soon as the obstruction is removed. That one of wheels 51 which is associated with the transversely adjustable cleat guide 21, will be splined upon shaft 57 so as to automatically partake of the transverse adjustment of its cleat guide. 105

In order to separate the on-coming cleat so as to insure the entry of the spacing tips 53 or 55 between the cleats, the lower corner of the tenon 32'' of each cleat may be beveled, as illustrated in Fig. 14 to form a pocket 60 into which the spacing tips may drop, but this arrangement is probably not the preferable one. As a preferred arrangement there is provided adjacent each cleat 110 guide, a rock shaft 61 carrying an arrester pawl 62 the tip of which is normally held in sliding engagement with the sides of the cleats and is adapted to drop into the space 63 formed by beveling one shoulder of the 115 120 125 130

cleat adjacent the tenon 32". The lower end of shaft 61 carries an arm 64 which is engaged by a light spring 65 tending to drive the pawl 62 to the position indicated in dotted lines in Fig. 9 and this arm 64 is carried into the path of movement of four cams 66 carried by the adjacent wheel 51.

The sheet material 71 needs to be definitely spaced and located with relation to the cleats to which it is to be secured and it is therefore desirable that any gage member which is provided be arranged to coact with the ends of the cleats. For that purpose there is provided a sheet-gage finger 72 at each side of the machine. Each of these fingers has a main portion which fits between the adjacent ends of two cleats and also has an upwardly extending sheet-gage 73 which projects above the upper faces of the cleats and has a thickness which is just sufficient to properly space the sheets. Each finger 72 is carried by a longitudinally movable carriage 74 mounted in a guideway 75 and is projected inwardly by a light spring 76. The carriage 74 is yieldingly drawn rearwardly by means of a weighted cord 77, or otherwise, and is propelled forwardly by the forwardly moving cleats. In the forward end of guideway 75 is a cam 78 adapted to be engaged by a roller 79 carried by finger 72 so as to automatically withdraw the finger 72 from between the cleats.

The operation of the stapling mechanism is intermittent, being accomplished by the reciprocation of the stapling head 81 in an ordinary manner and, in the present type of machine, this stapling action has to take place during a period when the blank material is at rest. It is therefore necessary to produce an intermittent advancement of the spaced-cleat carriers 45 and for that purpose each of these carriers at its forward end is carried over a driving sprocket 82 carried by a shaft 83. Each shaft 83 carries a beveled pinion 84 meshing with a beveled gear 85 carried by shaft 86, one of the gears 85 being splined upon shaft 86 so as to partake of the lateral adjustment of the laterally adjustable cleat-guide 21. Secured to shaft 86 is a ratchet wheel 87 engaged by pawls 88 carried by a lever 89 connected by a pitman 91 with the main drive shaft 92 of the machine, in a well-known manner. In order to avoid any drag of the inner ends of the fingers 72 upon the cleats during the return movement of said fingers, a guide 93 may be provided for the return movement of roller 79, a pivoted gate 94 being arranged between this guide and cam 78, as illustrated in Fig. 15.

The operation is as follows: A feeding operative will deliver cleats in proper length sequences to the receiving ends of the channels 31 and, as this feeding operative has nothing to do but to place the cleats, it is

possible for the single operative to supply cleats to both channels. The cleats, when so delivered, are carried forward by the chains 33 and, if said chains are provided with lugs 34, the action of the chain will be intermittent depending wholly upon the obstructive action of pawls 62 and chains 45. The first cleat will enter the space between the feeding chains 45 and abutment 48 and be positively engaged by said feeding chains 75 and drawn forwardly step by step. The forward end of the next cleat will be closely associated with the rear end of the first cleat, and the finger 54 of wheel 51 will occupy the position occupied by the middle one of fingers 52 in Fig. 8, the cam edge 56 of finger 54 resting against the side of the first cleat and the tip 53 of the first finger 52 resting against the side of the cleat. As the rear end of the first cleat approaches pawl 62 said pawl will drop into the space 63 and form an obstruction to the further advancement of the second cleat whereupon the first cleat will continue in its forward movement and, when the rear end of its tenon passes the first spacing tip 53 said spacing tip will drop in behind the rear end of tenon 32" of the first cleat 32. As soon as this occurs the appropriate cam 66 of wheel 51 will engage the adjacent arm 64 and withdraw pawl 62 from the path of movement of the second cleat, whereupon the chains 33, which are driven at a faster speed than that of chains 45, will cause the second cleat to catch up with the first cleat and to engage the spacing tip 53 100 which has been inserted, whereupon the second cleat will enter under control of the chains 45 and said chains will thereafter maintain the proper spacing of the cleats until after the stapling mechanism has been 105 passed. As soon as the second cleat is well under control of the chains 45 the first spacing tip 53 is withdrawn from between the cleats and the second spacing tip comes into position against the side of the second cleat 110 ready for entry behind the second cleat as soon as its rear end is brought to proper position. Until such time, however, the driving belt 58 is continually slipping upon the pulleys of shaft 57. The above action is repeated until the fourth cleat has been 115 brought under the control of chains 45 at which time the forward spacer 55 is in position to drop in behind the third cleat and at this time the movement of the wheel 51 120 is sufficient to bring both of the pins 55 into position behind the third cleat before the appropriate cam 66 withdraws pawl 62. Consequently, a longer space between the fourth cleat of the one-blank and the first 125 cleat of the next blank is provided. Before the cleats reach the stapling mechanism finger 72 is automatically projected between the separated ends of the two cleats and as soon as this projection occurs the principal 130

operative, who supervises the operation of the stapling mechanism, places the sheet material 71 upon the cleats, the members 73 forming an abutment for positioning the forward edge of the sheet, and the operative holds the sheet in position as the cleats are advanced step-by-step until enough of the forward edge of the sheet has passed beneath the stapling mechanism to permit the insertion of one or two staples. As soon as this occurs the operative may remove his hands and the material will be automatically advanced beneath the stapling heads. At about this time rollers 79 engage the cams 78 so that fingers 72 are withdrawn from between the cleats and the weighted cord 77 causes an immediate return of said fingers to position where they may be again automatically projected between the ends of 20 the next cleats.

The preliminary feeding mechanism, comprising the chains 33 and channels 31, is not absolutely essential because the cleats may be fed by hand directly to the spacing wheels 51 but with such an arrangement it is probable that a cleat feeding operative would be required for each cleat guide. It will be readily understood that while I have shown only two cleat guides, the addition of one or 30 more cleat guides with appropriate feed spacing mechanism would not depart from my invention and would not require the exercise of invention.

It will be seen from the above that accurate spacing of the cleats (which is commercially very necessary in order to produce a rigid box) is entirely automatic and that the spacing mechanism is a fixed and definite portion of the mechanism so that it cannot 40 become misplaced or improperly arranged and that its operation is entirely automatic and entirely independent of the lengths of cleats. It is therefore possible, without any adjustment of any kind, to produce boxes 45 having the same length but of different widths and depths by merely feeding cleats to the spacing mechanism in proper length sequences. It will also be noticed that at each forth cleat a greater space is automatically provided and that there never can be any mistake in the provision of this additional space, so that a proper tying length of the binding wire is automatically assured.

Claims

55 1. In a box blank machine, the combination of a cleat guide, cleat-feeding means for positively feeding simultaneously a plurality of spaced cleats along said guide, stapling mechanism arranged to operate upon such 60 cleats while under control of the cleat-feeder, a cleat-spacer arranged at the entrance end of the cleat-feeder, said cleat-spacer being movable into co-operative relation between a cleat under the control of the cleat-feeder and a cleat not 65 yet under the control of the cleat-feeder,

cleat-feeder, and withdrawable from between said cleats after the second cleat has passed under control of the cleat-feeder, and a yielding preliminary cleat-feeder delivering to said spacer. 70

2. In a box blank machine, the combination of a cleat guide, cleat-feeding means for positively feeding simultaneously a plurality of spaced cleats along said guide, stapling mechanism arranged to operate upon such 75 cleats while under control of the cleat-feeder, a cleat-spacer arranged at the entrance end of the cleat-feeder, said cleat-spacer being automatically movable into co-operative relation between a cleat under the control of the cleat-feeder and a cleat not yet under the control of the cleat-feeder, and automatically withdrawable from between said cleats after the second cleat has passed under control of the cleat-feeder, and a 80 yielding preliminary cleat-feeder delivering to said spacer.

3. In a box blank machine, the combination of a cleat guide, cleat-feeding means for positively feeding simultaneously a plurality 90 of spaced cleats along said guide, stapling mechanism arranged to operate upon such cleats while under control of the cleat-feeder, a cleat-spacer arranged at the entrance end of the cleat-feeder, said cleat-spacer being 95 movable into co-operative relation between a cleat under the control of the cleat-feeder and a cleat not yet under the control of the cleat-feeder, and withdrawable from between said cleats after the second cleat has 100 passed under control of the cleat-feeder, a yielding preliminary cleat-feeder delivering to said spacer, an interrupter arranged to intermittently interrupt the cleats in the preliminary cleat-feeder to permit placing of 105 the cleat-spacer, and means for intermittently withdrawing the interrupter.

4. In a box blank machine, the combination of a cleat guide, cleat-feeding means for positively feeding simultaneously a plurality 110 of spaced cleats along said guide, stapling mechanism arranged to operate upon such cleats while under control of the cleat-feeder, a cleat-spacer arranged at the entrance end of the cleat-feeder, said cleat-spacer being automatically movable into co-operative relation between a cleat under the control of the cleat-feeder and a cleat not 115 yet under the control of the cleat-feeder, and automatically withdrawable from between 120 said cleats after the second cleat has passed under control of the cleat-feeder, a yielding preliminary cleat-feeder delivering to said spacer, an interrupter arranged to intermittently interrupt the cleats in the preliminary cleat-feeder to permit placing of 125 the cleat-spacer, and means for intermittently withdrawing the interrupter.

5. In a box blank machine, the combination of a cleat guide, cleat-feeding means for 130

positively feeding simultaneously a plurality of spaced cleats along said guide, stapling mechanism arranged to operate upon such cleats while under control of the 5 cleat-feeder, a cleat-spacer arranged at the entrance end of the cleat-feeder, said cleat-spacer being movable into coöperative relation between a cleat under the control of the cleat-feeder and a cleat not yet under the 10 control of the cleat-feeder, and withdrawable from between said cleats after the second cleat has passed under control of the cleat-feeder, and a preliminary cleat-feeder 15 delivering to said spacer.

6. In a box blank machine, the combination of a cleat guide, cleat-feeding means for positively feeding simultaneously a plurality of spaced cleats along said guide, stapling mechanism arranged to operate 20 upon such cleats while under control of the cleat-feeder, a cleat-spacer arranged at the entrance end of the cleat-feeder, said cleat-spacer being automatically movable into coöperative relation between a cleat under the 25 control of the cleat-feeder and a cleat not yet under the control of the cleat-feeder, and automatically withdrawable from between said cleats after the second cleat has passed under control of the cleat-feeder, and a preliminary 30 cleat-feeder delivering to said spacer.

7. In a box blank machine, the combination of a cleat guide, cleat-feeding means for positively feeding simultaneously a plurality of spaced cleats along said guide, stapling mechanism arranged to operate 35 upon such cleats while under control of the cleat-feeder, a cleat-spacer arranged at the entrance end of the cleat-feeder, said cleat-spacer being movable into coöperative relation 40

45 tion between a cleat under the control of the cleat-feeder and a cleat not yet under the control of the cleat-feeder, and withdrawable from between said cleats after the second cleat has passed under control of the cleat-feeder, a preliminary cleat-feeder delivering to said spacer, an interrupter arranged to intermittently interrupt the cleats in the preliminary cleat-feeder to permit placing of the cleat-spacer, and means for 50 intermittently withdrawing the interrupter.

8. In a box blank machine, the combination of a cleat guide, cleat-feeding means for positively feeding simultaneously a plurality of spaced cleats along said guide, 55 stapling mechanism arranged to operate upon such cleats while under control of the cleat-feeder, a cleat-spacer arranged at the entrance end of the cleat-feeder, said cleat-spacer being automatically movable into coöperative relation between a cleat under the control of the cleat-feeder and a cleat not yet under the control of the cleat-feeder, and automatically withdrawable from between 60 said cleats after the second cleat has passed under control of the cleat-feeder, a preliminary cleat-feeder delivering to said spacer, an interrupter arranged to intermittently interrupt the cleats in the preliminary cleat-feeder to permit placing of the cleat-spacer, and means for 65 intermittently withdrawing the interrupter.

70 In witness whereof, I have hereunto set my hand and seal at Indianapolis, Indiana, this sixteenth day of June, A. D. one thousand nine hundred and ten.

ARTHUR M. HOOD. [L. S.]
